(57) **CLAIM**

The ornamental design for a Augustus door handle, substantially as shown and described herein.

DESCRIPTION

FIG. 1 is a perspective view of the inventive augustus door handle together with a broken-line circle, where the broken-line circle represents an environmental generic key or latch cover which forms no part of the claimed design;

FIG. 2 is a front view thereof;

FIG. 3 is a left side view thereof;

FIG. 4 is a right side view thereof;

FIG. 5 is a top view thereof; and,

FIG. 6 is a bottom view thereof.

It is understood that the broken lines throughout the drawings are environmental only and form no part of the claimed design.
